UNITED STATES PATENT OFFICE.

HARRY E. BUSH, OF SEATTLE, WASHINGTON, ASSIGNOR, BY MESNE ASSIGNMENTS, OF ONE-HALF TO WESTERN PATENT RIGHT AND INVESTMENT COMPANY, OF SEATTLE, WASHINGTON, A CORPORATION OF WASHINGTON.

FENCE-WIRE TWISTER.

No. 820,909.

Specification of Letters Patent.

Patented May 15, 1906.

Application filed July 6, 1905. Serial No. 268,390.

To all whom it may concern:

Be it known that I, HARRY E. BUSH, a citizen of the United States, residing at Seattle, in the county of King and State of Washington, have invented certain new and useful Improvements in Fence-Wire Twisters, of which the following is a specification, reference being had therein to the accompanying drawings.

10 The object of this invention is the provision of improved means of simple and inexpensive construction whereby pickets may be expeditiously and reliably woven into a fence in a uniform and substantial manner and 15 that, too, by simply giving the operating device a swinging movement.

The invention consists of the novel construction of the details of the invention and the peculiar combination and arrangement 20 thereof, as will be hereinafter described with reference to the accompanying drawings, wherein—

Figure 1 is a perspective view of an embodiment of my invention shown operatively 25 connected to a fence being constructed therewith, and Fig. 2 is an enlarged side elevation of a portion of the invention shown partly in section.

In said drawings the reference-numeral 1 30 represents a bar having formed or provided thereon operating-handles 2 and 3, respectively, extending in a vertical and transverse direction. Fixedly secured, as by stud-bolts 4 and nuts 5, to the bar are annular guide- 35 frames 6 for the rotary members 7. These members are each provided with a plurality of antifriction-wheels 8, mounted on axles 8', which are journaled in said members and extend into grooves 9, provided in the inner 40 peripheral surfaces of said guide-frames. A pair of apertures 10 are provided in each of said members in proximity of its outer edge and are preferably disposed in an arm 7' thereof, which for increased rigidity is protruded into the aforesaid frame-grooves.

Integrally formed on each frame 6 and preferably at its upper end is a laterally-projecting arm 11 for the purpose of spacing the pickets in proper position in the fence to be 45 woven.

In constructing a fence the wires 12 are disposed in pairs arranged at distances apart equal to the distances between the axes of the said rotary members and are reliably secured to a fence-post, such as 13, and thence 55 they are passed through the respective apertures 10 and severally secured to tension devices 14, connected by strap-wires 15, passing around winding take-up drums 16, as shown, to an adjacent post, as 17. These 60 tension devices may be of any suitable and convenient form, but preferably of the type illustrated in Fig. 1, wherein are a number of posts 18, about which the fence-wires are alternately passed, and thereby affording sufficient obstruction to the drawing of the 65 wires to insure the proper tension.

In practice it is oftentimes advantageous to bring the fence-wire from spools positioned to the left of the said tension devices and 70 secure the ends to the post 13, thus enabling the progress of the work to be continuous and without necessitating the splicing of the ends until all of the wire has been used from the 75 spools.

The wires being passed through the apertures of the rotary member and strung along between the posts, as before mentioned, with tension applied thereto, the wires are simultaneously twisted one or more times by imparting a rotary swinging movement to the bar. A picket is then placed in position between the wires and forced into proper alignment and spacing from the post by being pressed equally toward the latter through 80 the contacting of the arms 11 with the picket. The bar is then manipulated, as before explained, to twist the wires and secure the picket being attached, and so on. The wires can be twisted as many times as desirable 85 between any two pickets and in opposite directions in consecutive spaces.

The advantages of the invention will be understood from the foregoing, and it is perfectly adapted for the purposes for which intended.

Having described my invention, what I claim as new, and desire to secure by Letters Patent, is—

In a device of the class described, the com- 100

bination of an operating-bar provided with handles, annular guide-frames attached to said bar, each frame being formed with an interiorly-disposed groove, a rotary member mounted in each guide-frame, each rotary member being formed with a plurality of arms, antifriction-wheels mounted in the said arms and running in said groove, each member being formed also with an arm protrud-

ing into said groove, said arm being provided with a pair of apertures in proximity to its outer edge.

In testimony whereof I affix my signature in presence of two witnesses.

HARRY E. BUSH.
